(57) **CLAIM**

The ornamental design for a chart for edibles, as shown and described.

DESCRIPTION

FIG. 1 is a front perspective view of a chart for edibles, showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is left-side elevation thereof;

FIG. 7 is a right-side elevation view thereof; and,

FIG. 8 is an exploded top perspective view.

The broken lines shown in the drawings depict portions of the chart for edibles that form no part of the claimed design.
